DESIGN FOR A FISH LURE

Berlee M. Potter, El Dorado, Kans.

Application June 6, 1946, Serial No. 130,471

Term of patent 14 years

(Cl. D31—4)

To all whom it may concern:

Be it known that I, Berlee M. Potter, a citizen of the United States, residing at El Dorado, in the county of Butler and State of Kansas, have invented a new, original, and ornamental Design for a Fish Lure, of which the following is a specification, reference being had to the accompanying drawing, forming part thereof.

Figure 1 is a side elevation of a fish lure, showing my new design.

Figure 2 is a top plan view thereof.

Figure 3 is a front elevation.

Figure 4 is a rear elevation of the same.

I claim:

The ornamental design for a fish lure, as shown.
BERLEE M. POTTER.
